HAND ROCK DRILL

James C. Wright, Colorado Springs, Colo.

Application December 22, 1936, Serial No. 117,166

6 Claims. (Cl. 255—42)

My invention relates to manually operated drilling mechanism for use of miners and the like.

My object is to provide an easily operated and cheaply constructed drill mechanism of this character having manual feeding means, automatic feeding means, and automatic chuck rotating means. Other objects will appear as the description progresses.

10 Figure 1 represents a side view of the drill; Fig. 2, a front end view; Fig. 3, a rear end view; Fig. 4, a detail rear view showing a part of the automatic feeding means; Fig. 5, a longitudinal interior view of the drill with the near half of the housing removed; Fig. 6, a fragmentary view showing the locking lug engaging the hammer; Fig. 7, a transverse sectional view on secant line 7—7 of Fig. 5; and Fig. 8, a transverse sectional view on secant line 8—8 of Fig. 1.

20 Although I show the preferred embodiment of my invention, I do not thereby limit myself to the precise form shown, but wish it understood that within the scope of what hereinafter is claimed, various changes in the details of construction may be made without departing from the spirit of the invention.

This device comprises a base; a support; a housing; manually operated feeding means; a hammer member; operating means for the hammer member; a steel holding chuck; means to rotate the chuck; automatic feeding means; and disengaging means for the automatic feeding means.

The base 1 is provided with a pair of guide channels and hinged to a support 4 by hinge members 5 connected by pins 6. The housing 7 is provided with a pair of guide ledges 8—9 which are disposed in the guide channels. An end member 10 is secured to the rear end of the housing 7 by bolts 11.

The manually operated feeding means comprise an actuating nut 12 provided with a ratchet 13 and disposed in end member 10; a feed screw 14 screwed through the nut 12 and journalled 45 in a vertically disposed bearing plate 15 which is secured to a pair of rods 16 which are secured to the base 1; and a crank 17 mounted on the end of feed screw 14 and secured thereto by a nut 18. A manually operated pawl 19 having a 50 knob 19A is secured to the plate 15 by a screw 20 and adapted to engage a hexagonal portion 21 on the feed screw 14. A pawl 22 is mounted on a pivot 23 in the end member 10 and is adapted to engage the ratchet 13 to prevent backward rotation of the nut 12.

The hammer member is provided with a spring receiving portion 25; an intermediate portion 26; a hammer head portion 28, and a guide portion 28A; and is slidably disposed in the housing 7. The intermediate portion 26 is provided with a rack 29 and a journal 30. The spring receiving portion 25 is provided with an inclined face 31, and the guide portion 28A contains a key 32 which works in a key way 33 in the housing 7.

The operating means for the hammer member 10 comprises a spring 34 disposed about the portion 25 of the hammer member within the housing 7 and is compressed by the mechanism now to be described. A roller 35 is mounted on journal 30 on the hammer member. A transversely 15 disposed actuating shaft 36 is journalled in housing 7. An intermittent gear 37 is mounted on shaft 36 and is adapted to engage the rack 29 intermittently. An intermittent cam 38 is mounted on shaft 36 and is adapted to cooperate 20 with the roller 35. A pinion gear 39 is mounted on shaft 36 outside the housing 7. A drive shaft 40 is journalled in the bearings 41 on the housing 7. A spur drive gear 42 is mounted on shaft 40 and meshed with the pinion 39. A shaft 43 is 25 journalled in bearing 44 on housing 7. A pinion gear 45 is mounted on shaft 43 and meshed with spur gear 42. A fly wheel 46 is mounted on shaft 43. Cranks 71—72 are mounted on shaft 40.

A steel holding chuck 47 is provided with a 30 ratchet 48 and rotatably mounted in the housing 7.

The means to rotate a chuck 47 comprises an eccentric cam 49 mounted on shaft 36; a lever 50 mounted on a stud 51; and a click mechanism. 35 The lever 50 is provided with a roller 52 adapted to follow the eccentric cam 49. The click mechanism comprises a hollow stud 53 on the lever 50; a spring 54 disposed in the stud 53; and a thimble 55 provided with an engaging head and 40 disposed on the spring 54. A retaining pawl 57 is mounted on a pin 58 and is adapted to engage the ratchet 48 to prevent backward rotation of the chuck.

The automatic feeding means comprise a vertically disposed slide 59 slidably mounted in the end member 10 and provided with a stud 60 upon which a roller 61 is mounted, the roller 61 being disposed against the inclined face 31 of the hammer member; and a pawl 62 mounted on 50 a stud 63 and adapted to engage the ratchet 13.

The disengaging means for the automatic feeding means includes a bell crank having arms 64—65 mounted on a bolt 67 and is adapted to engage a pin 68 on the slide 59. An annular 55

plate 69 is disposed about the feed screw 14 adjacent to the nut 12 and is adapted to be clamped against the nut 12 by the arm 64 of the bell crank. A lever 70 is mounted on bolt 67.

5 For convenience in manufacture and assembling, the housing is divided longitudinally into two parts which are normally secured together by bolts.

10 A lug 75 is mounted on a shaft 76 journalled in the housing, and a lever 77 is mounted on shaft 76.

15 In use, the machine is properly located to drill into a rock and the steel S disposed in the chuck and allowed to protrude beyond the chuck into the housing as indicated by x. The housing which performs the function of a carriage, is adjusted by turning the crank 17 which revolves the feed screw 14 within the nut 12 and thereby moves the housing along the guide channels in 20 the base 1. Before the feed screw 14 can be re- volved, the pawl 19 must be swung backward to clear the nut 21. If the housing is to be moved backward, the lever 70 must be swung backward so as to disengage the automatic feeding means 25 and to brake and lock the nut 12. After the housing has been manually adjusted, the pawl 19 is swung back into position to engage the nut 21 to prevent rotation of the feed screw 14, and the lever arm 70 is swung back to normal so as 30 to permit the inclined face 31 to operate the slide 59.

35 After the manual adjustments have been made as described, the cranks 71-72 are turned manually. The drive gear 42 on shaft 40 engages the actuating pinion 39 on shaft 36 and actuates the cam 38 and the intermittent gear 37. The cam 38 cooperates with the roller 35 on the hammer member and moves the hammer member backward against the spring 34 until it reaches the limit of 40 its action, at which time the intermittent gear engages the rack 29 and drives the hammer member onward against the spring 34 until the intermittent gear 37 leaves the rack 29. When the teeth of the intermittent gear clears the rack 29, the compressed spring 34 forces the hammer members forward, causing it to strike the end portion x of the steel with a hammer like blow.

45 Each time the hammer member is moved backward, the inclined face 31 cooperates with the roller 61 and lifts the slide 59, thereby causing the pawl 62 to rotate the nut 12 the distance of one tooth of the ratchet 13. When the hammer member is driven forward, the slide 59 drops and the pawl 62 engages the next tooth of the ratchet 13. The action of the pawl 62 on the ratchet 13 screws the nut 12 forward on the feed screw 14 and thereby moves the housing forward.

50 The eccentric cam 49 on the shaft 36 cooperates with the roller 52 on the lever 50 and moves the thimble 55 along the periphery of the ratchet gear 48. The thimble 55 being disposed over a spring 54 on a stud 53, is permitted to slide over the teeth of ratchet gear 48 on its upward trip but is caused to engage the ratchet teeth on its downward trip and thereby revolve the chuck the distance of one tooth of the ratchet gear 48. It will be observed that the rotation of the chuck is accomplished during the backward movement of the hammer member.

55 The hammer member may be locked in the extreme backward position by swinging lever 77 so as to swing lug 75 into position in front of the point indicated by z on the hammer member, as shown in Fig. 6.

70 The steel is disposed slidably in the chuck and

if the housing advances faster than the drill enters the rock, the hammer member cannot make a full stroke, therefore the ratchet 13 is not engaged by the pawl 62. As soon as the drill advances far enough to permit the hammer member to make a full stroke, the pawl 62 engages the ratchet 13 and moves the housing forward. This is an automatic cut-out.

I claim:

1. In a rock drill, the combination of a guide shell; a housing slidably mounted on said guide shell; a feed screw extending from said guide shell; an end member secured to the rear end of said housing; a feed actuating nut mounted on said feed screw within said end member; a ratchet on said feed actuating nut; a hammer member slidably mounted in said housing and provided with an inclined face portion; a vertically disposed slide mounted in said end member and provided with a roller adapted to cooperate with the inclined face of said hammer member; an actuating pawl mounted on said slide and adapted to engage the teeth of the ratchet on said feed actuating nut; and a pin on said slide; a brake disc mounted on said feed screw adjacent to said feed actuating nut, a transversely disposed bolt mounted in said housing; a bell crank mounted on said bolt and adapted to cooperate with said brake disc to brake said feed actuating nut and to cooperate with said pin to lift said slide; a lever mounted on said bolt outside said housing.

2. In a rock drill, the combination of a guide shell; a housing slidably mounted on said guide shell; a feed screw extending from said guide shell; an end member secured to the rear end of said housing; a feed actuating nut mounted on said feed screw within said end member; a ratchet on said feed actuating nut; a hammer member slidably mounted in said housing and provided with an inclined face portion; a vertically disposed slide mounted in said end member and provided with a roller adapted to cooperate with the inclined face of said hammer member; an actuating pawl mounted on said slide and adapted to engage the teeth of the ratchet on said feed actuating nut; a pin on said slide; a brake disc mounted on said feed screw adjacent to said feed actuating nut; a transversely disposed bolt mounted in said housing; a bell crank mounted on said bolt and adapted to cooperate with said brake disc to brake said feed actuating nut and to cooperate with said pin to lift said slide; a lever mounted on said bolt outside said housing; a lug mounted on said lug shaft and adapted to engage said hammer member to prevent said hammer member from forward movement; and a lever mounted on said lug shaft outside said housing.

3. In a rock drill, the combination of a guide shell; a housing slidably mounted on said guide shell; a feed screw extending from said guide shell; an end member secured to the rear end of said housing; a feed actuating nut mounted on said feed screw within said end member; a ratchet on said feed actuating nut; a hammer member slidably mounted in said housing and provided with an inclined face portion; a rack on said hammer member; a shaft journalled in said housing; an intermittent gear on said shaft adapted to engage said rack intermittently; a spring disposed about said hammer member within said housing; a vertically disposed slide mounted in said end member and provided with a roller adapted to cooperate with the inclined face of said hammer member; an actuating pawl

- mounted on said slide and adapted to engage the teeth of the ratchet on said feed actuating nut; a pin on said slide; a brake disc mounted on said feed screw adjacent to said feed actuating nut; 5 a transversely disposed bolt mounted in said housing; a bell crank mounted on said bolt and adapted to cooperate with said brake disc to brake said feed actuating nut and to cooperate with said pin to lift said slide; and a lever 10 mounted on said bolt outside said housing.
4. In a rock drill, the combination of a guide shell; a housing slidably mounted on said guide shell; a hammer member slidably mounted in said housing; a roller mounted on said hammer member; a drive shaft mounted in said housing; an intermittent cam mounted on said drive shaft and adapted to cooperate with said roller to move said hammer member rearward; a lug shaft journalled in said housing; and a lug mounted on said 15 20 lug shaft and adapted to cooperate with said lug shaft to engage said hammer member and prevent forward movement thereof.
5. In a rock drill, the combination of a guide shell; a housing slidably mounted in said guide shell; a hammer member slidably mounted in said housing; a steel holding chuck provided with a ratchet and rotatably mounted in the forward

end of said housing; a chuck operating lever pivotally mounted on the outside of said housing; a click mechanism on the forward end of said chuck operating lever adapted to cooperate with the ratchet on said chuck; a drive shaft journalled in said housing; and a cam mounted on said drive shaft and adapted to cooperate with said chuck operating lever. 5

6. In a rock drill, the combination of a guide shell; a housing slidably mounted on said guide shell; a hammer member slidably mounted in said housing; a roller mounted on said hammer member; a rack on the underside of said hammer member; a drive shaft mounted in said housing; an eccentric cam, an intermittent cam, and an 15 20 25 intermittent gear mounted on said drive shaft, the intermittent gear being adapted to cooperate with said rack and the intermittent cam being adapted to cooperate with said roller; a chuck operating lever pivotally mounted on said housing and adapted to cooperate with the eccentric cam on said drive shaft; and a chuck mounted in the forward end of said housing and adapted to be rotated by the forward end of said chuck operating lever. 25

JAMES C. WRIGHT.
